RIDABLE BOUNCING TOY

Peter Ian Raphael, Cheadle Hulme, and John William Sutton, Macclesfield, England, assignors to Peter Raphael Limited, Stockport, Cheshire, England

Filed June 23, 1969, Ser. No. 17,828

Claims priority, application Great Britain Dec. 27, 1968

Term of patent 14 years

Int. Cl. D21—02

U.S. Cl. D34—15

—FIG. 1—

—FIG. 2—

FIG. 3

FIG. 4

FIG. 1 is a perspective view of a ridable bouncing toy, embodying our new design;

FIG. 2 is a top plan view thereof;

FIG. 3 is a side elevation thereof; and

FIG. 4 is an underneath plan thereof.

The characteristic feature of our design resides in the particular gripping configuration shown in combination with the inflatable base.

We claim:

The ornamental design for a ridable bouncing toy, as shown and described.
